ROLLING CLOSURE STRUCTURE

William F. Heckman, Newport, and Ottis C. Haggard, Dayton, Ky., assignors to Higgin Products, Inc., Newport, Ky., a corporation of Delaware

Application December 22, 1939, Serial No. 310,512

12 Claims. (Cl. 156—39)

Our invention applies to rolling closures for windows or other openings generally, including rolling window screens, shades, light-tight closures and the like; but is especially useful in connection with the last mentioned type of structure, and will be described in connection therewith in an exemplary embodiment.

In typical light-tight closure installations, such for example as are set forth in Traut Patent 1,947,070 of Feb. 13, 1934, a roller housing is installed at the top of the window opening; side guides are placed at the sides, and a bottom rail is provided. The closure is held on a spring roller in the housing, and is provided with a draw bar, riding in the side guides and making ultimate light-tight connection with the bottom rail as the closure is drawn down. The edges of the closure ride in the side guides; and in most installations it is necessary to provide transverse bars or braces for the closure itself, which are either incorporated in the closure or are slidable on the side guides and are lifted by the draw bar as it ascends. Light-tight connections have to be made between the side guides and the bottom rail and between the side guides and the roller housing, giving a rather elaborate interfitting structure. Moreover, wherever the roller housing, side guides or bottom rail contact the window opening, calking must be done to eliminate light leaks. The installation thus becomes a permanent part of the building and can be removed only with the utmost difficulty and with damage to the interior trim of the building.

Yet, when something goes wrong with the structure, as for example a rent or tear in the rolling closure itself, necessitating removal of the spring roller from the housing, the entire structure must be demounted. Roller housings have been made in which the front plate or panel could be removed; but this does not solve the problem since it is still necessary to remove the housing from the window opening if the spring roller is to be removed from the housing.

A fundamental object of our invention is the provision of a structure in which the spring roller can be removed from the housing and the rolling closure including the drawbar can be taken out of the structure without removing any part of the structure which is mounted against the window opening. Ancillary objects include the provision of a structure in which, upon removal of the spring roller, the relief of tension occurs without danger either to the operator or to other parts of the structure; the provision of a structure in which the operating parts are easily re-

moved and reassembled without the use of complicated or unusual tools; the provision of a structure which does not interfere either with the operation of securing initial tension or with the means by which tension may be adjusted during operation of the closure.

These and other objects of my invention which will be set forth hereinafter or will be apparent to one skilled in the art upon reading this specification, I accomplish by that certain construction and arrangement of parts of which I shall now describe the aforesaid exemplary embodiments.

Reference is made to the drawing, wherein:

15 Fig. 1 is a vertical elevation of a rolling closure installation.

Fig. 2 is a sectional view of the roller housing taken along the lines 2—2 of Fig. 1.

Fig. 3 is a sectional view of a side guide taken along the lines 3—3 of Fig. 1.

Fig. 4 is a sectional view through the housing, taken along line 4—4 of Fig. 1, showing an end plate embodying elements of our invention.

Fig. 5 shows an end plate showing the same elements in a stage of disassembly.

Fig. 6 is a transverse sectional view through the end plate taken along the lines 6—6 of Fig. 4.

Fig. 7 is a longitudinal sectional view of the roller housing and roller taken along the lines 30 7—1 of Fig. 4.

Fig. 8 is a perspective view of the end plate of Fig. 4.

Fig. 9 is a perspective view of the keeper device.

Fig. 10 is a view of an end plate showing another form of construction.

Fig. 11 is a partial view of an end plate showing still another form of construction.

In Fig. 1 we have shown a window or other opening 1, fitted with a rolling closure comprising a spring roller housing 5, side guides 8 and a bottom rail 9. A spring roller holding the actual closure 10 is located in the housing; and the closure has a drawbar 10a. We shall not further describe the general structure of the rolling closure but shall confine ourselves to a description of the means whereby the closure and roller may be removed from the structure without demounting any of the permanently installed parts of the rolling closure structure.

50 The spring roller housing 5 has a removable front plate 11 held on by screws or the like. It has already been pointed out that the side guides have light-tight interconnection with the spring roller housing. This connection is such as to permit the removal of the front plate 11. As shown

most clearly in Fig. 7 the housing 5 has end plates 12 and 13. The spring roller 14 is loosely mounted upon a shaft 15, the ends of which extend through the end plates 12 and 13. A spring 16 is interposed between a member 17 attached to the shaft and a member 18 non-rotatably connected with the roller. The member 18 can with advantage be made slidable within the roller, though rotation thereof is inhibited by a groove 19 (see Fig. 2) in the roller, which groove provides means for attachment of the rolling closure 20 to the roller. The member 18 forms a bearing for the roller on the shaft 15 near one end of the roller; and a bearing near the other end may be provided by a member 21.

In rolling closures of this type it is advisable to provide means for the adjustment of tension conditions. For this purpose the shaft 15 is provided at one of its ends with a beveled worm gear 22. This gear has a shank 23 which is pinned or keyed to the shaft and which extends through a perforation in the end wall 13. The beveled worm gear meshes with a worm 24 provided with suitable bearings 25 on the end plate 13. By rotating the worm the shaft may be turned in either direction, thus effecting an adjustment of tension. An end of the worm may be slotted as at 26 so that it may be engaged by a screwdriver or other tool, and the front plate 11 of the roller housing is perforated as at 27 in Fig. 1, so that tool engagement may be effected.

Following the principles of our invention, we provide the end plate 13 with a slot whereby the end of the shaft and the beveled worm gear may be removed from the plate in a forward direction. By reason of the bearing members 25 and centering ridges on the worm it is not possible to remove the end of the shaft and the worm gear in a direction parallel to the axis of the worm, unless the worm gear be brought out of engagement therewith. As a consequence, in our preferred form we slot the end plate 13 in a manner shown most clearly in Fig. 8. Here the slot terminates centrally of the plate in a portion 28 so positioned as to hold the worm gear in meshing relationship with the worm. Immediately beyond this point the slot sharply angles downwardly as at 29, and terminates toward the edge of the plate 13 in a horizontal portion 30. A keeper is provided as shown most clearly in Figs. 4, 5 and 9. This keeper comprises a part 31 which lies in the plane of the body of the end plate 13 and fills the slot therein to the extent of keeping the worm gear in the positioning portion 28. Fastened to the part 31, the keeper also has a part 32 which lies parallel to and against a face of the body of the end plate 13 and may be fastened thereto by a screw 33. The relationship of the parts when the keeper is in place is shown in Fig. 4.

In taking the spring roller and closure out of the roller housing the operations are as follows: the face plate 11 is removed, thus disclosing the roller. Next the keeper 31-32 is removed by taking out the screw 33 and pulling the keeper forwardly. The tension of the spring 16 on the shaft 15 (which in Figs. 4 and 5 tends to rotate the worm gear 22 in a counter-clockwise direction) serves to retain the gear and worm in engagement. Any suitable sort of hook is next engaged with the shaft 15 or with the worm gear 22 or its shank. A forward pull on the hook causes the worm gear and the end of the shaft to move forwardly in the slot. The immediate component of motion, however, produced by the slanting slot

portion 29 is downwardly so as to bring the beveled worm gear out of engagement with the worm. This relationship is shown in Fig. 5. Immediately disengagement is effected, any tension of the spring 16 is released through rotation of the worm gear; but it will be noticed first that the worm gear has been brought out of engagement with the worm and is free to rotate without destroying its teeth or those of the worm, and second that the tension is released while the shaft and spring rollers are essentially in the housing, so that there is no danger to the operator. The hook shaped tool which he is using does not rotate, of course, and the danger of serious injury has been done away with. The tension is released immediately, and the worm gear and shaft are drawn forwardly out through the slot so as to be wholly disengaged from the end plate 13. Next, by a slight axial movement of the shaft (to the right in Fig. 7) the left hand end of the shaft is pulled out of the perforation in the end plate 12. The shaft and spring roller are now free and out of the housing. The end of the closure can be drawn upwardly so as to disengage it and the drawbar from the side guides 8. Where sliding brace members 34 are employed these also are disengaged from the top of the side guides. In this way the spring roller assembly and the closure assembly can be taken out of the installation without demounting either the spring roller housing or the guides on the bottom rail.

The operation of re-installing the spring roller and closure assembly is the reverse of the operations described above. Our construction permits the usual practice of pre-tensioning the spring before installation. This is desirable because the complete tensioning of the spring by means of the worm and gear arrangement is time-consuming. It is the practice, while holding the roller to rotate the shaft to build up spring tension before inserting the shaft in the housing. This is done in the ordinary manner before the worm gear is engaged in the slot; and it has already been explained that the ultimate engagement of the worm gear with the worm holds the shaft in position in the slot, leaving the operator's hands free to insert and fasten the keeper.

Other forms of slot construction may be employed. In Fig. 10 we have shown a slot 35 which is a straight slot, but located aslant to the horizontal. The inner end of the slot terminates at a locating point for the gear but the slot itself has a sufficient downward slant to produce disengagement of the gear and worm prior to disengagement of the worm from the end plate. The keeper in this instance comprises the same essential parts 31a and 32a, the first mentioned part being disposed angularly to the second mentioned part.

Again as shown in Fig. 11, the slot 36 may be horizontal, but positioned below the level of the locating portion 37. When housing this form of slot, the initial motion of the gear during removal is straight downwardly and then horizontally outwardly. A suitable keeper in this instance comprises portions 31b and 32b. The portion 31b will be large enough to fill the horizontal portion of the slot so as to give to the gear support from beneath.

It may further be noted that our construction permits us to form the shank of the worm gear with a rib 38, leaving an annular groove between the rib and the worm gear 22. Thus the worm

gear is enabled to act as a centering means for the shaft.

Modifications may be made in our invention without departing from the spirit of it.

Having thus described our invention what we claim as new and desire to secure by Letters Patent, is:

1. In combination in a spring roller housing, an end plate, a shaft adapted to extend through said end plate, a gear on the end of said shaft having engagement with said end plate, a worm mounted on said end plate for turning said gear, and means removably retaining said gear on said end plate, said means comprising a removable keeper for said gear, said end plate having a slot therein permitting withdrawal of said gear when said keeper is removed.

2. In combination in a spring roller housing, an end plate, a shaft adapted to extend through said end plate, a gear on the end of said shaft having engagement with an end plate, a worm mounted on said end plate for turning said gear, and means removably retaining said gear on said end plate, said means comprising a removable keeper for said gear, said end plate having a slot therein permitting withdrawal of said gear when said keeper is removed, said slot having a portion for retaining said gear in engagement with said worm, and a removal portion, said removal portion having a downwardly extending part whereby upon removal of said gear, disengagement of said gear from said worm is effected prior to disengagement of said gear from said plate.

3. In combination in a spring roller housing, an end plate, a shaft adapted to extend through said end plate, a gear on the end of said shaft having engagement with an end plate, a worm mounted on said end plate for turning said gear, and means removably retaining said gear on said end plate, said means comprising a removable keeper for said gear, said end plate having a slot therein permitting withdrawal of said gear when said keeper is removed, said slot extending downwardly from a positioning portion whereby disengagement of said gear and said worm is effected prior to disengagement of said gear from said plate.

4. In combination in a spring roller housing, an end plate, a shaft adapted to extend through said end plate, a gear on the end of said shaft having engagement with an end plate, a worm mounted on said end plate for turning said gear, and means removably retaining said gear from said end plate, said means comprising a removable keeper for said gear, said end plate having a slot therein permitting withdrawal of said gear when said keeper is removed, said slot having a horizontal portion and a vertical portion whereby disengagement of said gear and said worm is effected prior to disengagement of said gear and said plate, said keeper having a horizontal portion lying within said slot and supporting said gear from beneath.

5. An end plate construction for a spring roller housing comprising a body, a worm rotatably mounted on said body, said body having a slot extending from a central position at which said slot may retain a worm gear in mesh with said worm to an edge of said plate, whereby said gear may be disengaged from said plate.

6. An end plate construction for a spring roller housing comprising a body, a worm rotatably mounted on said body, said body having a slot extending from a central position at which said

slot may retain a worm gear in mesh with said worm to an edge of said plate, whereby said gear may be disengaged from said plate, said slot having a portion extending downwardly from said central position whereby disengagement of said gear from said worm may be effected prior to disengagement of said gear and said plate.

7. An end plate construction for a spring roller housing comprising a body, a worm rotatably mounted on said body, said body having a slot extending from a central position at which said slot may retain a worm gear in mesh with said worm to an edge of said plate, whereby said gear may be disengaged from said plate, said slot having a portion extending downwardly from said central position whereby disengagement of said gear from said worm may be effected prior to disengagement of said gear and said plate, and a keeper having a portion for attachment to said plate and a portion lying within said slot for retaining said gear in said central position.

8. An end plate construction for a spring roller housing comprising a body, a worm rotatably mounted on said body, said body having a slot extending from a central position at which said slot may retain a worm gear in mesh with said worm to an edge of said plate, whereby said gear may be disengaged from said plate, said slot having a portion extending downwardly from said central position whereby disengagement of said gear from said worm may be effected prior to disengagement of said gear and said plate, and a keeper comprising a portion adapted to have face to face engagement with a face of said plate, and a portion lying within said slot for maintaining said gear in said central position, and releasable means for fastening said keeper to said plate.

9. In a rolling closure installation including a spring roller housing, side guides, and a spring roller, a construction permitting removal of said spring roller from said housing without demounting said housing from side guides, said construction comprising a removable front plate for said housing, end plates for said housing having engagement with said spring roller, one of said end plates being slotted whereby said spring roller may be removed therefrom, and a removable keeper for said end plate to retain said spring roller in position.

10. In a rolling closure installation comprising a spring roller housing with end plates, a spring roller having a shaft and side guides, a construction permitting removal of said spring roller from said housing without demounting it, said construction comprising means in connection with one of said end plates for removably retaining said shaft in position therein.

11. In a rolling closure construction comprising a spring roller housing, and a spring roller having a shaft with engagement in end plates of said housing, a construction permitting removal of said spring roller from said housing without demounting said housing, said construction comprising a removable front plate for the said housing, a tension adjustment means on an end plate of said housing, said end plate being slotted, said slot having a positioning portion for said shaft and a portion extending therefrom in a direction to enforce disengagement of said shaft from said tension adjustment means prior to disengagement of said shaft from said plate.

12. In a rolling closure installation comprising a spring roller housing, side guides, and a spring roller with a shaft engageable with end plates, a disconnectable spring tensioning device permit-

ting removal of said spring roller from said housing without demounting said housing, said device comprising a worm rotatably mounted on one of said end plates, a worm gear mounted on an end of said shaft, said end plate having a slot with a portion for positioning said worm gear in engagement with said worm and a removal portion,

extending therefrom in a direction to enforce disengagement of said worm gear and worm prior to disengagement and removal of said worm gear from said plate, and a keeper for retaining said worm gear in engaged position with said worm.
